Primary Examiner — Kevin K Rudzinski*Assistant Examiner* — Amber J Rabie(74) *Attorney, Agent, or Firm* — Bridgeway IP Law Group, PLLC; Jihun Kim; Hyun Woo Shin(57) **CLAIM**

The ornamental design for a case for an adapter, as shown and described.

DESCRIPTION

FIG. 1 is a front, top, right side perspective view of a case for an adapter, showing my new design;

FIG. 2 is a front elevation view thereof;

FIG. 3 is a rear elevation view thereof;

FIG. 5 is a left side elevation view thereof;

FIG. 6 is a right side elevation thereof;

FIG. 6 is a top plan view thereof;

FIG. 7 is a bottom plan view thereof;

FIG. 8 is a perspective thereof showing a configuration of use; and,

FIG. 9 is a perspective view thereof showing the case for an adapter in a closed configuration.

The broken lines in the drawings show portions of the case for an adapter that form no part of the claimed design. The broken lines in FIG. 8 showing an adapter in broken lines depict environmental subject matter that form no part of the claimed design.
